US00D495943S1

(12) **United States Design Patent**
Hentschel et al.

(10) Patent No.: **US D495,943 S**
(45) Date of Patent: **** Sep. 14, 2004**

(54) **ENTRY KEY PAD**

(75) Inventors: **Christopher Hentschel**, Kingston, MA
(US); **Brad Sampson**, Methuen, MA
(US)

(73) Assignee: **International Electronics, Inc.**,
Canton, MA (US)

(**) Term: **14 Years**

(21) Appl. No.: **29/191,043**

(22) Filed: **Sep. 30, 2003**

(51) LOC (7) Cl. **08-07**

(52) U.S. Cl. **D8/330; D8/343**

(58) Field of Search D8/330, 331, 343,
D8/347; 70/14, 20, 57, 277, 278.1, 278.4,
